[57] **CLAIM**

The ornamental design for a stylus for inputting electromagnetic signals into a tablet, as shown and described.

DESCRIPTION

FIG. 1 is a front elevational view of a stylus for inputting electromagnetic signals into a tablet showing my new design;

FIG. 2 is a rear elevational view thereof;

FIG. 3 is a right side elevational view thereof, the left side being the same in appearance as the right side;

FIG. 4 is a bottom plan view thereof;

FIG. 5 is a top plan view thereof;

FIG. 6 is a front elevational view of a second embodiment thereof;

FIG. 7 is a rear elevational view thereof;

FIG. 8 is a right side elevational view thereof, the left side being the same in appearance as the right side;

FIG. 9 is a bottom plan view thereof;

FIG. 10 is a top plan view thereof; and,

FIG. 11 is a front side perspective view of the first embodiment thereof.

FIG.1

FIG.2
